UNITED STATES PATENT OFFICE.

LEE E. MOORE AND WILLARD A. DAVIS, OF BOSTON, MASSACHUSETTS,
(CHARLES P. GAITHER EXECUTOR OF LEE E. MOORE, DECEASED,) AS-
SIGNORS TO THE DAVIS-MOORE SEWING MACHINE COMPANY, OF
SACO, MAINE.

TAKE-UP DEVICE FOR SEWING-MACHINES.

SPECIFICATION forming part of Letters Patent No. 399,685, dated March 19, 1889.

Application filed November 5, 1886. Serial No. 218,109. (No model.)

To all whom it may concern:

Be it known that we, LEE E. MOORE and WILLARD A. DAVIS, both of Boston, county of Suffolk, State of Massachusetts, have invented certain new and useful Improvements in Sewing-Machines, of which the following is a specification, taken in connection with the drawings accompanying and forming a part hereof, in which—

10 Figures 1 and 2 are side elevations from opposite sides of a wax-thread sewing-machine, showing our improvements. Fig. 3 is a section on dotted line *x x* of Fig. 1. Fig. 4 is a front elevation. Fig. 5 is a cross-section on dotted line *y y*, Fig. 2.

15 Our present invention is an improvement in the machine shown and described in a series of patents therefor and for the different parts thereof by Job A. Davis, of Boston, aforesaid, said patents having been issued November 23, 1886, and numbered 353,252 to 353,257, inclusive. Since a detailed description of the various parts of the machine will be found in said series of patents, it will be 20 unnecessary for us to refer in the present specification to other than the improvements which form the subject-matter thereof.

25 A is the frame of the machine, and B is the main shaft, to which power is applied by means of the belt-pulley D. The other end of the main shaft carries a case which contains a shuttle, the same in construction as is shown and described in the said patents above referred to. On the shaft B is secured a cam, E, which actuates a lever, F, which is pivoted to the frame of the machine at G, the upper end of the lever F being connected with a sliding bar, H, which forms part of the take-up mechanism. The forward end of the 30 bar H projects downwardly and is pivoted to a T-shaped lever, I, at J. (See Fig. 1.) The T-shaped lever is pivoted at K to the heating-box L, and is provided at either end of its arm with sheaves i set therein, over which the thread M passes. To prevent the thread from getting off the sheaves during the movement of the take-up arms, the guards or retaining-pieces N are provided, which project in a U 35 shape over the peripheries of the sheaves.

After the thread leaves the sheave at the forward end of the lever I it passes through a tube, O, which is connected with the heating-box, and is thereby heated, and so acts to keep the waxed thread in working condition, and from this tube the thread passes through the thread-carrier *a²* and directly to the needle. Before reaching the sheave at the rear end of lever I the thread passes through a checking or gripping device, which consists of a grooved pulley or sheave, P, and a vertically-sliding bar, R, Figs. 1 and 3. The sliding bar R is actuated by a leaf-spring, S, which bears upon its upper end, and which is secured to the top of the frame of the machine. This bar R is held in position on the frame 40 of the machine by screws *a*, which pass through slots in the bar, and thus permit of its vertical movement. The thread passes around pulley P, and a part or all of the lower end of the bar R is cut to correspond to the curve of the periphery of the pulley, with which it comes in contact when the said bar R is down. When the take-up is slack, or in position to allow the thread to be drawn forward to the work, the bar R is up, permitting 45 the free movement of pulley P and presenting no resistance to the movement of the thread. When the take-up is acting to draw the lower thread up into the work, the bar R is down, bearing on the pulley P, preventing its movement and preventing the paying out of the thread. This movement of bar R is accomplished by means of a pin, c, fast thereto, (see Fig. 1,) which comes in contact with the shoulder or inclined part *d* of the sliding bar 50 H. The bearing-surfaces of the gripping device are preferably so located (see Fig. 1) as to give the thread a straight course to the thread-carrier when the take-up is in its slack position. When the thread is free to move, 55 the bar H is at the end of its forward throw, raising the bar R and throwing the take-up arm I into the position shown in dotted lines, Fig. 1. A movement of the bar H in the opposite direction immediately allows the bar 60 R to drop, thus seizing the thread securely between it and pulley P, stopping the pulley 65 and preventing more thread from paying out.

The continued movement of the bar H oscillates the arm I to the position shown in full lines, Fig. 1, thus taking up the loop of thread below the work, and pulling the under thread 5 and the loop up into the work as far as may be desired. This mechanism, being of metal and being connected directly with or located adjacent to the heating-chamber L, is also kept warm, and the thread is not allowed to cool 10 or become hard.

What we claim is—

1. In a sewing-machine, the combination, with an intermittent thread-gripping device, of a take-up lever having two oppositely-extending thread-carrying arms.
2. In a sewing-machine, the combination, with the sliding bar H and its operating mechanism, of the three-armed take-up lever pivotally connected with said bar to be operated thereby, the sheaves or rollers i, carried 15 20

by the two opposite arms of said lever, and the guards N, overlapping said sheaves or rollers.

3. In a sewing-machine, the combination, with a take-up lever, of an intermittent 25 thread-gripping device consisting of the pulley P, the vertically-movable sliding bar R, having a projection, as pin c, a spring, as S, for pressing said bar against said pulley, and the horizontally-reciprocating sliding bar H, 30 having an incline or shoulder, as d, to engage said pin or projection and lift the said bar R out of contact with the said pulley to release the thread.

LEE E. MOORE.
WILLARD A. DAVIS.
